UNITED STATES PATENT OFFICE.

CORNELIUS CLARK, OF BROOKLYN, NEW YORK.

MAT.

SPECIFICATION forming part of Letters Patent No. 439,865, dated November 4, 1890.

Application filed September 7, 1888. Serial No. 284,816. (No model.)

To all whom it may concern:

Be it known that I, CORNELIUS CLARK, of Brooklyn, in the county of Kings and State of New York, have invented a certain new and 5 useful Improvement in Mats, of which the following is a specification.

I will describe the invention as carried out with a familiar material—ordinary cocoa fiber—to form the strands of the mat; but it 10 will be understood that other material may be used. The strands are bent so as to give the required open-work character to the mat.

I use two strands, each of which extends across the goods with the proper convolutions 15 and then returns straight. One strand enters and returns from one edge and the other from the opposite edge. The strands are held in place by stitching. The stitches proper are set angularly as follows: one in the straight 20 strand inclined to the right and one in the sinuous strand inclined to the left are connected together, and then another pair of stitches oppositely inclined are connected, and these form doubled stitches from the attachment of one loop or bend of the sinuous to 25 the straight strand.

The accompanying drawings form a part of this specification and represent what I consider the best means of carrying out the invention.

Figure 1 is a horizontal section of mat, showing both the relation of the strands and of the stitches; and Fig. 2 is a diagram showing the stitches on a larger scale.

Similar letters of reference indicate like parts in all the figures when they appear.

The mat may be produced by hand or by the aid of machinery. I will designate the strand which extends straight across the mat

40 A and the sinuous strand B. I will designate the four doubled stitches or stitches yoked together in pairs the first pair G and H and the second pair I and J. I will use supernumerals, as G', when necessary to designate special parts of each stitch.

45 To form the stitch G a bight of the thread or twine is carried upward through the straight strand A, inclined to the right, as shown by G', and back again at nearly the same 50 inclination, as shown by G². Next, before this stitch G is drawn tight the stitch H is ini-

tiated by carrying a bight first down inclined, as shown by H', thence back at nearly the same inclination, as shown by H², and thence through the bight of the stitch G, and is extended along to the right, as shown at H³. The thread is then extended singly to the right, as shown by E, and the second pair of stitches is commenced by carrying the bight of the thread downward inclined, as shown 60 by I', back again, as shown by I², and then carrying a bight of the thread upward inclined, as shown by J', downward inclined, as shown by J², and through the bight of stitch I and away to the right. Then I produce a dummy- 65 stitch K by carrying a bight of the thread or twine up nearly perpendicularly, (assuming the mat to be held as in the drawings,) and thence down again nearly perpendicularly, but sufficiently apart to take proper hold of 70 the cocoa or other strong fiber of the mat-strand A, and thence through the bight of the previous stitch J and away to the right, the stitch to the right being always engaged by a succeeding stitch, thus forming a continuous 75 and yielding or elastic chain. Thus I continue across the entire mat and back again as many times as required.

The forms of the sinuous bends are not essential, as I can make them any shape that 80 may be required, or that may be made by hand. I traverse alternately in opposite directions, feeding in one direction while the strand A is being gathered into the proper sinuous line and secured to the adjacent 85 straight edge of the strand B, and feeding in the opposite direction while the strand B is being gathered into the proper sinuous line and being secured to the straight portion of the strand A. I esteem it preferable in making mats of large size to traverse the operation across rather than the mat. I have in my experimental work held the mat still, except as it is moved the proper amount to bring the completed portion and the new strand into 95 the proper position for each traverse.

The enlarged view in Fig. 2 shows the junction of the straight with a single-looped or sinuous strand, such as obtains at one edge. (Shown as the upper edge of the mat in Fig. 1.) 100 After the work has been carried once across, the strand B is extended straight across on the

back-stretch, and now the straight strand is sewed not simply to one sinuous strand, but to two, one applying above and the other below the straight, as shown in the middle of Fig. 1; but the formation of the stitches is identical with the formation shown in Fig. 2. In each position the sinuous strand or strands being held in the proper position temporarily by the hands of the operator or by any suitable tool or machine, the several stitches are set and tightened, after which the bends are strongly held by the stitches.

There may be a margin formed of any number of circuits of one or both of the strands A B, or of a separate strand of the same or a different material applied and strongly stitched around the edge. The stitches are peculiar in the regularity of succession of the angular dummy-stitches, and particularly in the character of the stitches in being inconspicuous. They are formed by a sewing-machine or by other means, which cause the thread to traverse through two strands and then to return at a small angle. The width of the punctures appearing on the face side of the mat is very slight, so that when the thread is drawn with a proper tension to sink it a little below the adjacent portion of the strand the stitches are perfectly concealed.

It will be understood that the stitches are what are technically known as "chain-

stitches." They join the parts strongly and permanently and hold the several convolutions of the strands in position, while by reason of their being chain-stitches they are sufficiently elastic to allow the mat to be bent as much as ever required in practice.

The stitches may be made with a straight needle instead of a cord. It is only essential to my invention that they be arranged as shown, and that they be chain-stitches or other elastic stitches capable of yielding sufficiently without overstraining or breaking under all the conditions to which mats are exposed in practice in being stored, used, or cleaned.

I claim as my invention—

The mat described, composed of separate strands A and B, one extended straight and the other sinuously, united by elastic stitches G H I J, inclined and connected substantially as shown and adapted to serve as herein specified.

In testimony whereof I have hereunto set my hand, at New York city, this 4th day of September, 1888, in the presence of two subscribing witnesses.

CORNELIUS CLARK.
